UNITED STATES PATENT OFFICE

KURT REICHE, OF BERLIN-HALENSEE, GERMANY, ASSIGNOR TO STETTINER CHAMOTTE-FABRIK ACTIEN-GESELLSCHAFT VORMALS DIDIER, OF BERLIN-WILMERSDORF, GERMANY, A CORPORATION OF GERMANY

METHOD OF DRYING GRANULAR OR POWDERED MATERIAL BY MEANS OF A FLUID

Application filed September 22, 1930, Serial No. 483,444, and in Germany September 23, 1929.

My invention relates to improvements in the method of and apparatus for drying granular or powdered material by means of fluid, and more particularly in the method of drying, glowing, coking, cooling or otherwise treating the said material. The object of the improvements is to provide a method which is economical and effective in operation, and with this object in view my invention consists in first circulating the heating or cooling fluid alongside the outside of the container containing the material, and thereafter passing the said fluid through the said container and causing the same directly to act on the material.

Another object of the improvements is to provide a method and an apparatus in which the heating or cooling fluid is used for carrying the material to be treated through the container, and with this object in view my invention consists in constructing the intake end of a tubular container in the form of an injector, the fluid being admitted through the said injector at high velocity and drawing the material into the container.

Other objects of the improvements will appear from the following description.

For the purpose of explaining the invention an apparatus suitable for putting the method into effect has been shown in the accompanying drawing in which the same reference characters have been used in all the views to indicate corresponding parts. In said drawing,

Fig. 1 is a sectional elevation showing the apparatus, and

Fig. 2 is a sectional elevation taken on the line 2—2 of Fig. 1.

In the example shown in the drawing the apparatus comprises a block 1 of brick-work or other material having a zigzag passage arranged therein, the said passage comprising horizontal sections 2 alternately connected at opposite ends by semi-circular portions 21. The said passage is connected at its bottom with an intake passage 6 for the heating or cooling medium, and it is closed at its top end as is shown at 5.

Within the passage 2, 21 there is a tubular

the said tubular container being smaller in diameter than the passage 2, 21, thus providing an annular passage surrounding the container. The pipe 3 is open at its top end and the delivery pipe 24 of a funnel is concentrically passed into the same, so that an annular passage 25 is provided between the pipe 24 and the intake end of the pipe 3. At its bottom end 7 the pipe 3 opens into a container 8 connected by a pipe 9 with a fan or blower 10 and a delivery pipe 11. The pipes 7 and 9 are connected to the top of the container 8 and between the same a partition 26 is provided which extends from the top of the container to a point spaced from the bottom thereof.

When using the apparatus for drying loose material the fan 10 is started and hot gas such as air, waste gas or the like is admitted through the passage 6, and loose material to be dried is supplied through the funnel 4 and the delivery pipe 24 thereof. By the suction of the fan the hot gas is drawn through the passage 6 and the passage 21 where it heats the pipe 2, 3 and the material contained therein from without. At the top of the passage 2 the gas rushes through the annular passage 25 where it has injector action and draws the loose material from the pipe 24 and into the pipe 3. Within the pipe the gas further heats the loose material by direct contact and its velocity is such that it carries the loose material through the pipe 3. Finally it carries the dried material through the pipe 7 into the container 8, the loose material being deposited therein by reason of the sudden change of the direction of the flow thereof. The heating gas is delivered through the pipe 11 and it may be conducted to a heating system where it is again heated and dried for being again entered into the circuit. The materials carried by the gas through the pipe 3 are directly heated and dried within the pipe and further they are heated and dried by the hot gas flowing around the pipe. The current of gas has its highest temperature near the intake passage 6 and its lowest temperature within the portion 7 of the pipe. In the drawing the current of gas has been indicated by arrows shown in full lines and

the flow of the mixture of gas and loose material has been indicated by arrows shown in dotted lines.

Where the apparatus is used for cooling purposes cold gas is admitted through the passage 6. The function of the cooling medium will be understood without further description.

By my improved apparatus granular or powdered material such as coke, coal, gravel, sand and the like may be dried, glowed, cooled or otherwise treated, and by causing the gas to act first on the outside of the pipe and thereafter directly on the material, the heating or cooling effect is high and economical. The heating and cooling effect is particularly high in case of powdered or finally disintegrated loose material which floats within the current of gas.

In the figures I have shown an apparatus in which the passages for the gas and the material are arranged in zigzag, but I wish it to be understood that I do not limit myself to this feature. In some cases I may use rectilinear passages, and where curved passages are used care should be taken that the curved portions thereof such as the portions 21 are curved along large radii for reducing the resistance opposed to the flow of the gas and the material. In this respect particularly good results are obtained when providing helical passages.

I claim:

The herein described method of treating granular or pulverized material which consists in passing said material over a confined path, forcing a gas first over said path in external relation thereto and in indirect relation to the material therein, then passing said gas interiorly into said path into direct contact with said material, and increasing the velocity of said gas coincidentally with its passage into said path to such an extent that it carries the material therethrough in a suspended state.

In testimony whereof I hereunto affix my signature.

KURT REICHE.
